UNITED STATES PATENT OFFICE.

ARTHUR R. SCHWARZKOPF, OF MUSKEGON, MICHIGAN, ASSIGNOR TO THE BRUNSWICK-BALKE-COLLENDER COMPANY, OF CHICAGO, ILLINOIS, A CORPORATION OF DELAWARE.

GAME-COUNTER.

1,184,389.

Specification of Letters Patent.

Patented May 23, 1916.

Application filed August 16, 1915. Serial No. 45,684.

To all whom it may concern:

Be it known that I, ARTHUR R. SCHWARZKOPF, a citizen of the United States, residing at Muskegon, in the county of Muskegon and State of Michigan, have invented 5 certain new and useful Improvements in Game-Counters, of which the following is a specification.

This invention relates to game counters 10 adapted to be assembled on a wire or similar support and mounted within reach of the player to mark from time to time the points made by the player during the progress of the game.

15 It is the object of my invention to provide a counter of light non-breakable construction and of sufficient rigidity to withstand bending and distortion in the course of the rough and careless usage to 20 which it is subjected.

Other objects and advantages of my invention will be apparent as it is better understood by reference to the following specification when read in connection with the 25 accompanying drawing illustrating the preferred embodiment thereof in which—

Figure 1 is an elevation disclosing a plurality of my improved game counters mounted on the supporting wire; Fig. 2 is 30 a vertical section through one of the counters, and Fig. 3 is a vertical section on the line 3—3 of Fig. 2.

Referring to the drawings, 1 indicates a wire or other suitable support upon which 35 are arranged a plurality of game counters 2. The counters 2 comprise a shell, preferably of metal, made up of members 3 stamped to concavo-convex form and provided with central openings 4. The edges 40 5 of the members 3 are spun, as is clearly shown in Fig. 3, to provide a rigid joint therebetween.

In order that the counters may be prevented from bending and becoming otherwise 45 distorted under the rough and careless usage to which they are subjected it is desirable that some reinforcing means be provided and, therefore, before assembling the members 3, I insert the reinforcing members 6, preferably consisting of a wire helix which may be readily varied in length, to accommodate any variation in the size of the members 3, by clipping the end of the

wire forming the helix. Obviously, however, the reinforcing member 6 may be 55 otherwise formed so long as it provides a support for the opposite members 3 of the counter and an opening in alinement with the openings 4 in the members 3 through which the wire support 1 may pass. 60

Preferably washers 7 are arranged between the ends of the reinforcing member 6 and the concave faces of the members 3. The members 3 are thereby stiffened at the point which is subjected to greatest stress 65 as the counters are forced along the wire support during the progress of the game. The washers 7 are shaped to conform to the curvature of the members 3 and have inwardly directed lips 8 adapted to be disposed within the ends of the reinforcing member 6, whereby displacement of the member 6 is effectually prevented.

From the foregoing it will be apparent that I have perfected a game counter which 75 overcomes the defects of counters as known in the prior art, since my improved counter is unbreakable and is not liable to bending and distortion which cause other forms of metal counters to become unsightly and use- 80 less after a short period of use. My invention is particularly designed to replace the wood counters which are now universally used and which are frequently broken and are replaceable only by the difficult and 85 tedious operation of removing the supporting wire.

It will be apparent that various changes may be made in the form, construction and arrangement of the parts without departing 90 from the spirit and scope of the invention or sacrificing any of its material advantages, the form hereinbefore described being merely a preferred embodiment thereof.

I claim:

1. A game counter comprising a hollow shell having oppositely directed convex walls provided with central openings, and an axially arranged reinforcing member within said shell and engaging the inner sides of 100 said walls to prevent distortion thereof.

2. A game counter comprising a hollow metal shell consisting of a pair of members secured together at their edges, providing oppositely directed convex walls having central openings therein, and an axially ar- 105

ranged reinforcing member within said shell and engaging the inner sides of said walls to prevent distortion thereof.

3. A game counter comprising a hollow metal shell consisting of a pair of members having central openings therein and secured together at their edges, providing oppositely directed convex walls, an axially arranged reinforcing member disposed within said shell, and bearing members between the ends of said reinforcing member and the inner sides of said walls.

4. A game counter comprising a hollow metal shell consisting of a pair of members having central openings therein secured together at their edges, providing oppositely directed convex walls, a reinforcing member consisting of wire helix disposed within

said shell, and bearing members between the ends of said helix and the inner sides of 20 said walls.

5. A game counter comprising a hollow metal shell, consisting of a pair of members, each having central openings therein and circumferential interengaging beads where- 25 by said members are secured together, providing oppositely directed convex walls, an axially arranged reinforcing member disposed within said shell, and bearing members between the ends of said reinforcing 30 member and the inner sides of said walls.

ARTHUR R. SCHWARZKOPF.
